INVENTOR.
Victor L. Conaghan
BY *Dr. G. Charles*
ATTORNEYS.

UNITED STATES PATENT OFFICE.

VICTOR L. CONAGHAN, OF WICHITA, KANSAS.

OIL-WELL UNDER REAMER.

Application filed March 8, 1923. Serial No. 623,692.

To all whom it may concern:

Be it known that I, VICTOR L. CONAGHAN, a citizen of the United States, residing at Wichita, county of Sedgwick, and State of Kansas, have invented certain new and useful Improvements in Oil-Well Under Reamers, of which the following is a specification, reference being had to the accompanying drawings, which form a part of this application.

My invention relates to oil well adjustable under reamers.

The objects of my invention are as follows;

First; To provide a detachable instrument, that can be let down by the drilling rope and manipulated in an upward and downward movement.

Second; To provide a mechanism with concealed tensioning devices.

Third; To provide an under reamer whose cutting bits will contract to the inside diameter of the casing and expand immediately when passing through and out at the end of the casing.

Fourth; An under-reamer with expansive bits that will draw back in the end of the casing and automatically contract to the diameter of the casing without catching on the end of said casing.

Fig. 1 is an elevation of the mechanism without being connected to the cable. Fig. 2 is an end view showing the bits expanded. Fig. 3 is a partial sectional view through the shell inclosing the core to which is attached the reaming bits. Fig. 4 is a detailed view of the core. Fig. 5 is an end view of Fig. 4. Fig. 6 is a detail view of the spring and connecting rod. Fig. 7 is a detailed view of one of the bits. Fig. 8 is a view showing the position of the casing in the ground with the under reamer at the lower end in its operative position.

1 is the threaded portion of the shank 2, 45 said shank having a square portion 3 to which is applied a wrench for convenience to remove a connecting member which is socketed and threaded to receive the threaded portion 1, the said connection being attached to a cable which extends from the derrick down. The connecting member, cable and derrick are not shown in the drawings, except the connection and rope in Fig. 8. 4 is the shell which is keyed to the core 55 5, by means of a key 6, which passes through

a rectangular square 7 through the shell and the neck of the core, said openings registering with each other. The shell 4 and the shank 3 are integral and the lower end of said shell is notched to receive the shoulder 60 bearing of the under reaming blade. The core 5 has a shank 8, said shank is adapted to engage on the bottom of shank 3 and the key is the convenient means for holding said core in the shell while in operation, but 65 the force of the process of under reaming will have its bearing at 9 and 10 and also at the shoulders 11 on shearing bit 12, said shoulder contacting the shell at 13. The core 5 is housed to receive the shank 14 of 70 the under reaming blade at 15 and the connecting rod and spring are housed at 16 as shown in Fig. 5. At 17 is shown a spreading member functioning as a cam to expand the cutting edges 18 of the bits 12. 19 is a 75 connecting rod having a ball 20, said ball adapted to engage in a socket 21, and on said rod is placed a tension spring 22, said spring adapted to tension on shoulder 23 and against a head 24 on said pin. The tension 80 of said spring allows the cutting bits to contract under tension when entering the oil well casing and also assists in expansion of the cutting ends of said bits as required for enlarging the hole below the casing. 85

My experience in oil well drilling has been that at times there are occasions when the metal casing for the oil well, should be lowered and as a rule in the process of drilling with the ordinary gravity drill, the hole 90 below the casing is smaller in diameter than that of the casing and should the formation be a hard substance it is necessary to ream the hole equal to, or larger than the casing, after which it is possible to lower the casing to the point desired and add sections to the top as lowered. 95

To operate my device a connection is attached to the steel cable and said connection is adapted to screw tightly on the shank of 100 my under reamer, and then by pressing the shearing blades together, it is entered into the casing and then lowered to the depth where it passes through the casing and immediately the shearing blades are tensioned 105 outward by the springs and connections heretofore described, contacting the walls of the hole, then by an upward and downward movement, the blades will shear the side walls enlarging its diameter. Such modi- 110

fications may be employed in all parts of the mechanism as lie within the scope of the appended claims.

Having thus described my invention, 5 what I claim as new and desire to secure by Letters Patent is;

1. In oil well under reamers, a shell, having a shank, a portion of which is square, to engage with a wrench, the outer end of said shank being threaded to engage with a hoisting connection, said shell adapted to receive a core, said core with a plurality of tensioning means and shearing blades attached thereto, for the purpose set forth 15 and described.

2. In oil well under reamers, a shell, having a shank, with threaded means for en-

gaging an operating connection, said shell being notched at the opposite end in which shearing blades engage, a core, having a plurality of housings about its periphery, said housings having bearing shoulders formed therein to function as spring seat bearings, a shank on the end of said core to engage against the bottom of said shell, a cam member on the opposite end of said core to function as expansion means for said shearing blades and a plurality of shearing blades and pivotedly connecting rods, a spring on said rods, to function as tensioning means, 25 to expand the shearing blades to a flaring position, for the purpose set forth and described.

VICTOR L. CONAGHAN.
